US0D1060236S

(12) **United States Design Patent** (10) **Patent No.:** **US D1,060,236 S**
Yuan (45) **Date of Patent:** **** Feb. 4, 2025**

(54) **WIRELESS CHARGER**

(71) Applicant: **DONGGUAN YIFAN ELECTRONICS CO., LTD.**,
 Dongguan (CN)

(72) Inventor: **Jinrong Yuan**, Dongguan (CN)

(**) Term: **15 Years**

(21) Appl. No.: **29/888,134**

(22) Filed: **Mar. 28, 2023**

(51) LOC (15) Cl. **13-02**

(52) U.S. Cl.

USPC **D13/108**

(58) **Field of Classification Search**

(57) **CLAIM**

The ornamental design for a wireless charger as shown and described.

DESCRIPTION

FIG. 1 is a perspective view of a wireless charger showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken line portions of the wireless charger form no part of the claimed design.

1 Claim, 8 Drawing Sheets
